UNITED STATES PATENT OFFICE.

WINFRED MUDGE BROOKS, OF EAST ORANGE, NEW JERSEY, ASSIGNOR TO E. J. BROOKS
& CO., OF NEW YORK, N. Y., A CORPORATION OF NEW YORK.

BAG-SEAL.

1,151,509.

Specification of Letters Patent. Patented Aug. 24, 1915.

Application filed June 25, 1915. Serial No. 36,246.

To all whom it may concern:

Be it known that I, WINFRED MUDGE BROOKS, a citizen of the United States of America, and a resident of East Orange, in the State of New Jersey, have invented a new and useful Improvement in Bag-Seals, of which the following is a specification.

This invention relates to means for securely fastening and sealing the necks of bags of textile fabric or other articles with cords so as to insure the detection of any tampering therewith.

The present improvement is primarily additional to my patent dated January 26, 1915 No. 1,126,376, that is to say—the improved bag seal preferably has in combination a loop-forming cord adapted to embrace the neck of the bag and a compressible lead seal part having threading holes through which the ends of the cord protrude sufficiently to be pulled tight by some suitable means such as shown in my seal press cord tightening device, copending application Serial No. 28,064, said seal part being further constructed with projections on one side adapted to interact with recesses in the face of one of the dies, also preferably a central threading hole through which the two ends of the cord protrude and side holes parallel with said central hole to provide for a double loop of the cord, together with a metallic pin element combined with such loop-forming cord and apertured seal as shown in said patent.

The leading objects of this invention are to make sure of the interrelation of the cord loops and the metallic pin element so as to insure a permanent seal fastening and to provide means for firmly and tightly placing the said pin element into its proper position in the sealing operation.

A sheet of drawings accompanies this specification as part thereof, in which like reference characters refer to like parts throughout.

Figure 1 is a perspective view of the wire member of said pin element of the improved bag seal; Fig. 2 is a perspective view of the same provided with its pushing and pulling knob; Fig. 3 is a side view of the same showing the novel cord hole; Figs. 4 and 5 are perspective views of the main seal part showing its respective sides; Fig. 6 is a sectional view of said main seal part threaded with the loop-forming cord and with the pin

element in position upon one loop, preparatory to use; Fig. 7 is a like view of the improved seal with the cord partly tightened and the pin element inserted in the bag neck preliminary to final tightening and sealing; Fig. 8 is a side view of the neck of a bag sealed with the improved device.

The improved press fastenable seal is composed of a neck pinning element *a*, a main seal part *b* and a loop forming cord *c*. Said neck-pinning element is in turn composed of two members 1 and 2, the first of which is a piece of moderately hard wire, Fig. 1, preferably iron, having its heel end 3 crimped and its other end pointed. Upon the crimped end of this wire said member 2, which is a pushing, pulling and loop engaging knob provided with a transverse hole 5 through which the cord is passed, preferably and conveniently of lead is cast fast. A flat thumb-engaging end 4 facilitates the preliminary pushing of this pin through the folds of the bag neck and same can be embossed if desired. This element may of course be constructed in any other desirable or convenient way of one piece or more, the essential features being the pin shank and knob head having a transverse hole for the reception of the loop cord. The seal part *b* is a compressible casting of lead having a double width central threading hole 6, side holes 7, 8, parallel therewith and one or more transverse projections 9, 10, Fig. 4 on one side to interlock with a correspondingly recessed bed die in the seal press to prevent displacement in pulling the cords by the seal press cord tightener. The cord *c* is preferably a hard twine which is first passed through the hole in the head of the pin element and then so threaded through the holes of the main seal part as to produce two sealing loops with the pin threaded upon one of them, as shown in Fig. 6. The loops are first placed over the bag neck and the pin thrust through the folds and then through the central hole of the seal along with the two ends of the cord already threaded therethrough as shown in Fig. 7. The seal is then placed in a seal press and the cord ends drawn by means of the cord-tightener attachment to the desired tension thus compressing the loops about the neck of the bag and at the same time firmly pressing home the pin element. The seal is then compressed and the operation is completed.

- With the completed seal fastening it is impossible to remove the pin element without destroying the cord loop upon which it is threaded and without removing the pin element it is impossible to slip the fastening loops from the neck of the bag. Furthermore all uncertainty is removed as to the proper engagement of the loops with the pin element which is made positive.
- Having thus fully disclosed my invention I claim:
1. In combination with a loop-forming cord and a compressible seal part, the latter having means including a central threading hole to engage said cord—a neck-pinning element adapted to penetrate the neck of a bag and to extend through said central hole in said seal part and having a head provided with a transverse hole adapted to receive the loop cord and to be threaded upon one of the sealing loops, whereby in the sealing operation said pin element is drawn by the cords through the bag neck and seal part where it is secured by the final compression of the latter part.

Copies of this patent may be obtained for five cents each, by addressing the "Commissioner of Patents, Washington, D. C."

2. A press-fastenable seal having in combination a compressible seal part provided with three parallel threading holes and means for preventing the displacement of said seal when between the dies of a seal press, a loop forming cord adapted to be threaded through said seal part to form two adjacent sealing loops and a metallic pin element having a pointed shank adapted to penetrate the neck of a bag and then pass through the central hole of the seal part along with the ends of the loop cord and an enlarged head having a transverse hole adapted to receive said loop cord and to be threaded upon one of said sealing loops, whereby in the sealing operation said pin element is drawn by the cords through the bag neck and seal part where it is secured by the final compression of the latter part, all substantially as hereinbefore set forth.

WINFRED MUDGE BROOKS.
